UNITED STATES PATENT OFFICE.

JAMES HENRY TIFFT, OF EAU CLAIRE, WISCONSIN.

WORK-TALLYING DEVICE.

SPECIFICATION forming part of Letters Patent No. 783,330, dated February 21, 1905.

Application filed June 15, 1904. Serial No. 212,632

To all whom it may concern:

Be it known that I, JAMES HENRY TIFFT, a citizen of the United States, and a resident of Eau Claire, in the county of Eau Claire and State of Wisconsin, have invented a new and Improved Work-Tallying Device, of which the following is a full, clear, and exact description.

This invention relates to improvements in devices for automatically indicating or tallying the number of pieces of work turned out by a machine—such, for instance, as the number of sheets turned off in a printing-press—the object being to provide a tallying device in connection with a machine that may be set for any predetermined number of pieces of work that it is desired to include in one batch or set and that will cause an alarm or cause the stopping of the machine when the required number shall have been reached, thus relieving the machine attendant of considerable responsibility and loss of time.

I will describe a work-tallying device embodying my invention and then point out the novel features in the appended claims.

Reference is to be had to the accompanying drawings, forming a part of this specification, in which similar characters of reference indicate corresponding parts in all the figures.

Figure 1 is a front elevation of a tallying device embodying my invention. Fig. 2 is a longitudinal section thereof. Fig. 3 is a similar section, but showing the parts in a different position. Fig. 4 is a section on the line $y-y$ of Fig. 2. Fig. 5 is a section on the line $x-x$ of Fig. 2, and Fig. 6 is a section on the line $z-z$ of Fig. 4.

Referring to the drawings, 1 designates a casing having a longitudinal vertical partition 2 and having at its front a door 3, mounted to swing downward on a pintle 4, attached to the lower wall of the casing, and having a lock 5, so that the door may be securely fastened to prevent meddling with the interior mechanism to be hereinafter described. Spindles 6 extend through the partition 2, and mounted on each spindle is a number-disk 7. Each disk is provided with numerals from "0" to "9," and the periphery of the disk is provided with notches opposite the numerals.

Mounted to swing on each spindle rearward of the number-plate carried thereby is a key-plate 8. The key-plate has an opening 9, through which the spindle passes and permits of longitudinal movement of the key-plate 55 relatively to the shaft. The plate is held yieldingly against the shaft, however, by means of a spring 10, surrounding a pin 11, extended from the end wall of the opening 9, and the inner end of the spring engages 60 against the shaft. At one end the key-plate has a forward projection 12, provided with a lug 13 for engaging in any one of the series of notches formed on the periphery of the number-disk with which said plate coacts, and 65 extended downward from this forward projection 12 is a finger-piece 14, having a perforation 15, through which the number on the disk for which the disk is set may be seen, and this number is also disclosed through a 70 sight-opening in the front wall of the casing, the opening being provided with glass, as indicated at 16.

Mounted to slide on the partition 2 rearward of each number-disk is a latch-plate 17. 75 As here shown, screws 18 pass from the partition 2 through slots in the latch-plate, and the plate is provided with a slot to receive the spindles 6, and extended from the upper end of the plate at right angles thereto is an arm 80 19, having a curved or cam surface 20 on its under side designed to be engaged by a reverse cam-surface 21 on the upper end of the key-plate. The several latch-plates are held yieldingly downward in engagement with an 85 actuating-rod 22, by means, as here shown, of a ribbon-spring 23, which is secured at its ends to pins 24 on the front of the partition 2, and this spring engages with the upper ends of the several latch-plates. Between 90 the latch-plates the spring passes underneath pins 25 on the partition. The actuating-rod 22 is movable lengthwise in the casing, and it is provided with notches 26, the bottom walls of which are inclined upward in the 95 direction of movement of the rod, and they are designed to receive the reversely-inclined lower ends of the latch-plates, as clearly indicated in Fig. 3. The rod is also provided with a locking-notch 27, designed to receive 100

a spring-pressed locking-pawl 30, mounted on the casing-partition. The actuating-rod 22 is moved in an actuating direction when released by the several latch-plates by means 5 of a spring 31, surrounding the outer end of said rod and engaging at the inner end with the end of the casing 1 and at the outer end with a collar or nut 32 on the rod. The opposite extended end of the rod 22 carries a 10 striker 33 for sounding an alarm-gong 34 to indicate when the tallying device is at the end of its registering movement. The shaft of the units-disk—that is, the disk shown at the right-hand end of the casing—has attached to it a ratchet-wheel 35, engaged by a pawl 36, mounted on an actuating-lever 37, arranged to swing on said shaft and movable in a slot 37^a, this lever being designed to be operated to cause movements of the disks by being engaged by a movable part of the machine at 15 intervals—that is, for instance, upon each complete operation of the machine for finishing a single piece of work. The said lever 37 is moved in one direction or to normal position, 20 as here shown, by means of a spring 38. Arranged on the units-disk shaft between the partition and the rear wall of the casing is a disk 39, carrying a finger 40, designed at each 25 complete rotation of the units-disk to engage 30 with a tooth on a wheel 41, carried by the shaft of the next number-disk or tens-disk, this wheel 41 being provided with a finger 42 for engaging with a tooth of the next actuating-wheel of the series upon the complete rotation 35 of the tens-disk, and this is carried out to the end in the usual manner.

In the operation the device is to be placed at any suitable point on a machine whereby 40 a rotary or other movable part will at intervals engage with the lever 37. The several number-disks are to be set or turned with the "0" at the top, and then the key-plates are to be turned to engage the lugs thereon in the notches of the disks opposite the numbers designed to be registered, these key-plates of course thus being arranged to rotate with the disks. When the number on which the key-plate is placed reaches the extreme top portion, said key-plates engage and lift the 45 releasing-latches, thus disengaging the said latches from the actuating-rod 22. Should it be the last disk, the said disk will stop and hold the latch out of engagement with the actuating-rod; but the other latches will still engage 50 with said rod until it comes their turn to be permanently released. When all of the latches shall have been raised, the actuating-rod 22 will be moved forward by the spring 31 to cause the shifting of a belt on the machine, 55 and thus stop the same, or to reverse a controlling switch of an electric motor. It will be understood that the release of the actuating-rod does not necessarily stop the action of the tallying device. The movement may

continue and designate the number exceeding 65 the number to which the finger or tallying device was originally set. This not only insures the safety of the device from damage, but is beneficial inasmuch as it shows what number has overrun the number the machine 70 is set for; but when the desired number is reached the striker 33 will engage the gong 34, and thus give the signal.

Having thus described my invention, I claim as new and desire to secure by Letters Patent— 75

1. A tallying device adapted to be used in connection with a machine and operated by a movable part thereof, comprising a casing, a plurality of number-carrying disks arranged therein and operated one from another, an actuating-lever arranged to be engaged by said movable part of the machine, an actuating-rod, and latch-plates slidable transversely of the number-disks for engaging with said rod and movable out of said engagement by the 85 number-carrying disks.

2. For use in connection with a machine for tallying a number of pieces of work, a casing, a plurality of number-carrying disks arranged in the casing and operated one from another, 90 an actuating-lever adapted to be engaged by a movable part of the machine, a spring-pressed rod movable lengthwise of the casing, latch-plates for engaging with said rod, key-plates carried by the disks, and cam portions on said 95 key-plates for engaging with and elevating the latch-plates.

3. A tallying device comprising a casing, a plurality of number-carrying disks arranged in the casing, each disk having peripheral 100 notches opposite the numbers, an actuating-rod movable lengthwise of the casing and having notches, latch-plates having sliding relation to the disks and adapted to engage in said notches, cam projections on the upper ends 105 of said latch-plates, and key-plates adjustable on and carried by the disks.

4. A tallying device comprising a casing, spindles arranged in the casing, number-carrying disks mounted on the spindles, means 110 for actuating the disks one from another, an actuating-lever having connection with one of the disks, a spring-pressed rod movable lengthwise of the casing and having notches, latch-plates movable longitudinally with relation to the disks and adapted to engage in 115 said notches, each latch-plate having a forward projection, key-plates movable on the spindles, means for securing the latch-plates as adjusted on the disks, the said key-plates having portions for engaging the forward projections of the latch-plates, and perforated finger-pieces extended from the upper ends of 120 said key-plates over the front of the disks.

5. A tallying device for the purpose specified comprising a casing, a plurality of number-carrying disks arranged in the casing and operated one from another, a spring-actuated 125

rod extended through the casing and provided with notches, a locking-pawl for engaging in one of said notches, latch-plates rearward of the disks for engaging in the others of said 5 notches, latch-plates having forward projections at the upper end, key-plates adjustable on the disks and having portions for engaging with the latch-plates for releasing the same from said rod, and an alarm operated by a 10 movement of said rod.

6. A tallying device for the purpose specified, comprising a casing having a longitudinal vertical partition, spindles having bearings in said partition, numeral-disks mounted on 15 the spindles, key-plates having slots through which the spindles pass, cam-surfaces on the ends of said key-plates, springs for holding the key-plates as adjusted with relation to the disks, an actuating-rod movable through the 20 casing, latches mounted to slide on the partition and adapted to engage with said rod, and cam projections on the latch-plates adapted

to be engaged by the cam-surfaces of the key-plates.

7. A tallying device for the purpose specified comprising a casing, a plurality of numeral-disks arranged therein and operated one from another, the said disks having peripheral notches, an actuating-rod movable through the casing, latch-plates rearward of the disks 30 and adapted to slide into and out of engagement with said rod, key-plates adjustable on the disks, lugs carried by the key-plates for engaging in notches of the disks, and means carried by the key-plates for raising the latch- 35 plates out of engagement with said rod.

In testimony whereof I have signed my name to this specification in the presence of two subscribing witnesses.

JAMES HENRY TIFFT.
